Primary Examiner—T. Chase Nelson*Assistant Examiner*—Kathleen M Sims(74) *Attorney, Agent, or Firm*—Tara M. Hartman; Barnes & Thornburg LLP(57) **CLAIM**

We claim the ornamental design for an appliance wave trim, as shown and described.

DESCRIPTION

FIG. 1 is a front perspective view of the appliance wave trim showing our new design;

FIG. 2 is a front elevational view of the appliance wave trim of FIG. 1; and,

FIG. 3 is a first side elevational view of the appliance wave trim of FIG. 1, with the second side elevational view being a mirror image of FIG. 3.

The rear elevational view, the top plan view, and the bottom plan view are not shown and form no part of the claimed design. The portion shown in broken lines is for illustrative purposes only and forms no part of the claimed design.
